ABSTRACT OF THE DISCLOSURE

Compounds of the formula

I

where

R1 is alkyl or alkoxy each having from 1 to 4 carbon atoms or phenyl;

R2 is alkoxy having from 1 to 6 carbon atoms if R1 is alkyl or phenyl, amino, alkylamino or dialkylamino each having from 1 to 6 carbon atoms, or alkenylamino having from 1 to 4 carbon atoms;

R3 is hydrogen or alkyl having from 1 to 4 carbon atoms; R4 is hydrogen, alkyl having from 1 to 4 carbon atoms, or halogen;

X is oxygen or sulfur;

are useful pesticides in the agricultural and veterinary fields.

The present invention relates to novel 4-thiochromanyl-(d,i)-thiophosphonic acid esters, 4-thiochromanyl-(d,i)-thiophosphonic acid esters, 4-thiochromanyl-(d,i)-thiophosphonic and -phosphoric acid ester amides of the formula

I

where

R1 is alkyl or alkoxy each having from 1 to 4 carbon atoms or phenyl;

R2 is alkoxy having from 1 to 6 carbon atoms if R1 is alkyl or phenyl, amino, alkylamino or dialkylamino each having from 1 to 6 carbon atoms, or alkenylamino having from 3 to 6 carbon atoms;

R3 is hydrogen or alkyl having from 1 to 4 carbon atoms; R4 is hydrogen, alkyl having from 1 to 4 carbon atoms, or halogen;

X is oxygen or sulfur;

with the proviso that R1 and R2 cannot both be alkoxy.

The novel compounds have excellent insecticidal, acaricidal and nematocidal properties.

2

As substituents, the following radicals may for example be cited:

R1=methyl, ethyl, n-propyl, isopropyl, n-butyl, isobutyl, secondary butyl, tertiary butyl, phenyl;

5 R1, R2=methoxy, ethoxy, n-propoxy, isopropoxy, n-butoxy, isobutoxy, secondary butoxy, tertiary butoxy, R2 also hexyloxy;

R2=methylamino, ethylamino, diethylamino, n-propylamino, n-butylamino, di-n-butylamino, n-hexylamino, allylamino;

R3=methyl, ethyl, n-propyl, tertiary butyl;

R4=fluorine, chlorine, bromine, methyl, ethyl, n-propyl, isopropyl, n-butyl, isobutyl, secondary butyl.

15 Preferably used are those (d,i)-thiophosphonic acid esters and (d,i)-thiophosphoric acid ester amides in which R1 is alkyl having from 1 to 4 carbon atoms and R2 is alkoxy having from 1 to 4 carbon atoms, or R1 is alkoxy having from 1 to 4 carbon atoms and R2 is amino, alkylamino or dialkylamino having each from 1 to 3 carbon atoms or allylamino. Preferred radicals R3 and R4 are:

R3=hydrogen, methyl, ethyl;

R4=hydrogen; fluorine, chlorine or bromine in 6- or 7-position.

25 For the preparation of the compounds of formula I, 4-halogeno-thiochromanyl compounds of the formula

II

30 where Hal is halogen, especially chlorine or bromine, are reacted with phosphorus compounds of the formula

III

40 or salts of such phosphorus compounds, if necessary in the presence of an acid binding agent.

The phosphorus compounds of formula III react easily with the 4-halogeno-thiochromanes of formula II, at temperatures in the range of from 0° to 120° C., preferably from 10° to 80° C. It is recommended to operate in the presence of a solvent or diluent inert to the reactants, especially lower aliphatic ketones, such as acetone or methylethylketone; alkanols, such as methanol, ethanol or isopropanol; esters, such as acetic acid ethyl ester; nitriles; N-alkylated acid amides, such as dimethylformamide; ethers, such as dioxan, glycol-dimethyl ether or tetrahydrofuran; aromatic hydrocarbons, such as benzene or toluene; halogenated hydrocarbons, such as chloroform or carbon tetrachloride, and water, as well as mixtures of such solvents with water.

45 The reaction proceeds with exchange of the halogen atom of formula II. Therefore, it is carried out either with addition of acid binding agents, or using salts, especially 50 alkali metal or ammonium salts of the phosphorus compounds of formula III. Preferred acid binding agents are alkali metal hydroxides and alkali metal carbonates; but tertiary nitrogen bases, for example pyridine or triethylamine, may also be employed.

55 The starting compounds of formula II and their preparation are described partly in French Patent Specification No. 1,584,755, partly in copending application Ser. No. 293,134 filed concurrently herewith.

60 The starting compounds of formula III are known and can be easily prepared according to usual methods.

65 The compounds of formula I are suitable for the destruction of numerous pests in crop plants including their

development stages, and they have insecticidal as well as acaricidal activity. Thus, different spider mite species, for example the European red mite (*Metatetranychus ulmi*), or mites like *Panonychus citri* or *Tetranychus urticae*, among them also strains resistant to phosphoric esters can be controlled with good results.

Also numerous biting and sucking insects noxious to crop plants can be destroyed by the compounds of the invention, for example beetles, such as the Mexican bean beetle (*Epilachna varivestis*), the Colorado beetle (*Lipitomona oryzarum*), the flower beetle (*Epicometis decemlineata*), the flea beetle (*Phylloreta spp.*), the strawberry boorer (*Coenorrhinus germanicus*), or the boll weevil (*Anthonomus grandis*); butterflies and their larvae, such as the Egyptian and the Old World boll worm (*Earias insulana* and *Heliothis armigera*); leaf rollers, especially the codling moth (*Carcocepsa pomonella*), the green oak leaf roller (*Tortrix viridana*), the tortrix moth (*Capua reticulana*), the corn borer (*Ostrinia nubilalis*) or the winter moth (*Operophtera brumata*); aphids, such as the bean aphid (*Doratis fabae*), the green peach aphid (*Myzodes persicae*), the cotton aphid (*Aphis gossypii*); or bugs, such as milkweed bugs and cotton stainers (*Oncopeltus fasciatus*).

The compounds of the invention are also suitable for combating ectoparasites living on productive livestock. Thus, mallophaga, lice (Anoplura), fleas (Aphaniptera), mites and ticks (Acarina, such as ixodids (Ixodidae), argasides (Argasidae), dermanyssides (Dermanyssidae); sarcoptides (Sarcoptidae), among them also those resistant to phosphoric esters, are destroyed.

Finally, the compounds are also suitable for combating nematodes species noxious to plants.

or liquid inert carrier substances, adhesives, wetting and dispersing agents, or grinding auxiliaries in the form of wettable powders, emulsions, suspensions, dusting powders, granules, flybands, products for spreading and washing. They may be mixed with other insecticides, fungicides, nematocides and herbicides.

As carrier material, mineral substances may be used, for example aluminium silicates, argillaceous earths, kaolin, chalks, siliceous chalks, talcum, kieselguhr or hydrated silicic acids, or preparations of these mineral substances with special additives, for example chalk with sodium stearate. As carrier material for liquid preparations, all usual and suitable organic solvents may be employed, for example toluene, xylene, acetone alcohol, isophorone, gasolines, paraffin oils, dioxan, dimethyl formamide, dimethyl sulfoxide, ethyl acetate, butyl acetate, tetrahydrofuran, chlorobenzene and the like.

Suitable adhesives are glue-like cellulose products or nonadhesive resins.

As wetting agents, all suitable emulsifiers may be used, for example ethoxylated alkylphenols, salts of aryl- or alkylaryl-sulfonic acids, salts of ethoxylated benzenesulfonic acids. Or some polyvinyl alcohols.

Suitable dispersing agents are cellulose pitch (salts of naphthalenesulfonic acid or, in certain cases, hydrated silicic acids or kieselguhr), or soaps.

As grinding auxiliaries, suitable inorganic or organic salts for example sodium sulfate, ammonium sulfate, so-

substances, for example, sodium sulfate, ammonium sulfate, sodium thiosulfate, sodium carbonate and sodium bicarbonate, sodium thiosulfate, sodium stearate, or sodium acetate may be used.

The content of the active ingredients in accordance with this invention in the ready-for-use products is generally from 2 to 95%. These active substances may also be combined with other known active ingredients in the formulations.

Simple formulations suitable for the activity tests may be obtained in the following manner.

6 g. of active substance are ground with 6 g. of finely dispersed silicic acid, and subsequently mixed in a mixer to obtain a wettable powder.

the following manner.

EMULSIFIABLE CONCENTRATE

3,816,456

4

6 g. of active substance are ground with 6 g. of finely dispersed silicic acid, and subsequently mixed in a mixer with 48 g. of a mixture containing 13.3% of dried cellulose waste liquor, 65.3% of quartz and aluminium silicates; 5.3% of finely dispersed silicic acid, 4.7% of polypropylene-glycol and 1.3% of the sodium salt of oleymethyleauride. Thus, 60 g. of a 10% wettable powder are obtained.

EMULSIFIABLE CONCENTRATE
2 g. of active substance, 16 g. of cyclohexanone and 2 g. of alkylaryl-polyglycol ether alcohol are mixed with each other. 20 g. of a 10% emulsifiable concentrate are obtained. The active substances to be used in accordance with the present invention in the veterinary field are applied normally by spraying, dusting or dipping methods, as well as, in the special case of the anti-tick agents, in the so-called dip or spray equipment.

The following examples illustrate the invention.

GENERAL PRESCRIPTION

2. Preparation of a halogenothiophromane derivative

0.1 mole or a tetrahydro-urethane or formate II is added, at room temperature and with agitation, to a solution or suspension of 0.10 to 0.11 mole of a salt of a phosphorus compound of formula III in 200 ml. of glycol-dimethyl ether. Stirring is continued for about 3 to 5 hours at 50° C., the precipitated salt is separated by sucrose-filtration, the filtrate is diluted with about 400 ml. of benzene, the organic phase is thoroughly washed with water and dried over Na_2SO_4 . After having distilled off the solvent, the products of the process are obtained as oils.

According to this process as indicated above, the following compounds are obtained:

EXAMPLE 39

Young apple trees planted in pots and heavily infested with a phosphoric ester resistant strain of the European red mite (*Metatetranychus ulmi*) were sprayed, until beginning drip-off with the aqueous dilution of an emulsifiable concentrate containing 0.003 weight percent of the compound of Example 13, and subsequently placed in a greenhouse at 20° C.

A microscopic control after 8 days showed that all mobile and immobile stages were killed.

The following commercial phosphoric acid esters used in comparative tests showed no activity even at higher concentration:

phenkapton, 0.025 weight percent, no effect
demeton-S-methyl, 0.05 weight percent, no effect
dimethoate, 0.05 weight percent, no effect.

Tested in the same manner, the compounds of Examples 1, 9, 15, 17, 19, 28 and 33 proved to be of equal activity.

EXAMPLE 40

Horse beans (*Vicia faba*) heavily infested with bean aphids (*Doralis fabae*) were sprayed, until beginning drip-off, with the aqueous dilution of an emulsifiable concentrate containing 0.000375 weight percent of the compound of Example 3. The sprayed plants were then placed at 20° C. in a greenhouse; evaluation was carried out 24 hours after spraying. All aphids were killed.

Tested in the same manner, the compounds of Examples 1, 2, 8, 10, 13, 15, 23, 25 and 30 showed equal activity.

EXAMPLE 41

Young cotton plants (*Gossypium spec.*) in pots, infested with African cotton strainers (*Dysdercus fasciatus*), were sprayed, until drip-off, with the aqueous dilution of a wettable powder concentrate containing 0.006 weight percent of the compound of Example 23. Subsequently, the plants containing the bugs were put into cylindrical gauze cages and placed in a greenhouse at 20° C. A control after 48 hours showed that all cotton strainers were killed.

Tested in the same manner, the compounds of Examples 1, 3, 28 and 33 showed the same good activity. The following phosphoric acid esters tested comparatively showed activity only at a considerably higher concentration:

Lethal concentr.
Diazinone 0.025% of AS
Dimethoate 0.025% of AS
Azinphos-ethyl 0.05% of AS

NOTE: AS=active substance. % = weight percent.

EXAMPLE 42

Larvae (4th stage) of the Mexican bean beetle (*Epiclachna varivestis*) and leaves of the dwarf-bush bean (*Phaseolus vulgaris*) were sprayed, by means of a spraying apparatus, with a dosed amount (corresponding to an application amount of 600 liters of spray liquor/ha. in the open fields) of the aqueous dilution of an emulsifiable concentrate containing the preparation of Example 10 in a concentration of 0.002 weight percent. The leaves and beetle larvae were placed in open vessels at 22° C. The control 47 hours after spraying proved that all larvae were killed.

Tested in the same manner, the compounds of Examples 1, 3, 15, 17, 21, 23 and 25 had equal activity.

EXAMPLE 43

In vitro test on ticks of the *Boophilus* species

- (1) *Boophilus microplus*
(a) strain of normal sensitivity
(b) Biarra strain, resistant

- (c) Mackay strain, resistant
(2) *Boophilus decoloratus*, resistant strain

For the preparation of a suitable formulation, 10 parts by weight of active substance were dissolved in 100 parts by volume of a mixture of cyclohexanone and nonylphenol (10 EO, 8:1), and the emulsifiable concentrate so obtained was diluted with water to attain the desired concentration.

10 adult female ticks of the cited species and different sensitivity to phosphoric esters, which had sucked themselves full of blood, were dipped for 5 minutes into these dilutions. Subsequently, the ticks were stuck with their dorsal side onto an adhesive tape and kept in a warming closet (28° C., about 80% of relative air moisture) for oviposition.

Two weeks after treatment the activity of the formulations was determined by evaluating the inhibition of oviposition expressed in percent; 100% inhibition meaning that all ticks treated with one active substance concentration did not oviposit, 0% meaning that all ticks did oviposit.

TABLE II.—IN VITRO TEST ON TICKS OF DIFFERENT PHOSPHORIC ESTER SENSITIVITY

Example	Concentration of active substance in percent	Inhibition of oviposition in percent

We claim:

1. A compound selected from the group consisting of 4-thiochromanyl-(di)-thiophosphonic acid esters, 4-thiochromanyl-(di)-thiophosphonic and -phosphoric acid ester amides of the formula

where

R_1 is alkyl or alkoxy each having from 1 to 4 carbon atoms or phenyl;

R_2 is alkoxy having from 1 to 6 carbon atoms if R_1 is alkyl or phenyl, amino, alkylamino or dialkylamino each having from 1 to 6 carbon atoms, or alkenylamino having from 3 to 6 carbon atoms;

R_3 is hydrogen or alkyl having from 1 to 4 carbon atoms;

R_4 is hydrogen, alkyl having from 1 to 4 carbon atoms, or halogen;

X is oxygen or sulfur.

2. The compound of the formula

3. The compound of the formula

4. The compound of the formula

5. The compound of the formula

6. The compound of the formula

7. The compound of the formula

8. The compound of the formula

9. The compound of the formula
